BAG FILLING APPARATUS

Jacob J. Neuman, South Salem, N. Y.

Application August 26, 1942, Serial No. 456,161

18 Claims. (Cl. 259—72)

This invention relates to new and useful improvements in bag filling machines and is an improvement over the bag filling machines of prior Patents 1,823,283, granted Sept. 15, 1931, and 2,159,858, granted May 23, 1939.

In the bag filling machines disclosed in the above mentioned prior patents, separate units were employed to hold the bags and to shake the same during the filling operation, each of which units was separately mounted and supported from ceiling beams with the result that the supporting structure for such units could not be standardized due to various ceiling heights and beam locations. Thus, erection costs in the field were relatively high. Furthermore, as disclosed in Patent 2,159,858, the bag holding unit and the shaking unit were operated by fluid pressure for which piping, pressure reducing valves, air reservoir, etc. had to be installed in the field. Once the machine was erected, it could not be moved to a new location without the expenditure of considerable time and labor.

One of the primary objects of the present invention is to overcome the above noted disadvantages in bag filling machines heretofore employed and to provide a combined bag holding and shaking unit which is compact, self-contained and portable.

Another object of the invention is to provide improved means for firmly holding an open-mouth bag or like receptacle in an expanded position for feeding of material into the same and also to shake the contents during the filling for the purpose of compacting the material.

A further object of the invention is to provide a unitary machine having both the holder and the shaker operated by a common prime mover embodied into the machine so that the entire machine may be moved as a unit from place to place as needed and be quickly and easily installed without requiring dismantling of any of the parts.

Still another object of the invention is to provide a novel motor-driven unit for operating the bag holding means and the shaking means intermittently.

A still further object of the invention is to provide a novel operating mechanism for the bag-holding means embodying a crank action and a clutch device for controlling the crank action.

The above together with other objects and novel features of the present invention will become more apparent from the following description with reference to the accompanying drawings in which numerals of like character have

been used to indicate similar parts throughout the several views.

Referring to the drawings—

Fig. 1 is a view in side elevation of the portable bag filling machine forming the subject-matter of the present invention with one wall of the upright frame removed to show the operating mechanism for the bag holder and shaker, and with parts of the bag holding means shown in section;

Fig. 2 is a vertical section taken along line 2—2 of Fig. 1;

Fig. 3 is a top plan view of the machine shown in Fig. 1 with certain parts broken away and in section;

Fig. 4 is an enlarged detail view of the bag holding means;

Fig. 5 is a section taken along line 5—5 of Fig. 4;

Fig. 6 is an enlarged detail of the motor-driven mechanism for operating the bag holding and the shaking means of the filling machine, showing the clutch and clutch operating mechanism;

Fig. 7 is a section taken along line 7—7 of Fig. 2 showing the eccentric drive and connection forming the shaking means; and

Figs. 8 and 9 are enlarged detail views of the clutch operating cam device.

In the drawings, referring more particularly to Figs. 1 and 2, the machine comprises a pair of channel members 10 and 11 suitably spaced apart to accommodate therebetween the usual bag conveyor 12 running over roller 12a and shown with an adjustable mechanism generally indicated as 12b for taking up slack in the conveyor belt. The channel members 10 and 11 form a supporting base for an upright frame F preferably divided into an intermediate section 13 and a top section 14, the latter hingedly supporting at its upper end by means of a transverse shaft 15 journaled therein, one end of a laterally projecting arm 16 which extends over the conveyor 12 and supports at its free end the bag holders 17 and 18 and cooperating bag clamping members 19 and 20. The over-all height of the machine should be such that when the bag is clamped on the bag-holders 17 and 18 by the clamping members 19 and 20, respectively, there will be a clearance of about 2 or 3 inches between the bottom of the bag and the conveyor. Moreover, the channel members 10 and 11 are of such a height as to provide the necessary clearance for various conveyor heights that may be encountered in different installations.

As best seen from Figs. 4 and 5, each of the

bag-holders 17 and 18 terminates at its upper end in flanges 21 which extend laterally from opposite sides of the holders and are slidable along tracks 22 formed by angle irons suitably secured to the inner surfaces of downturned edges 23 of the arm 16. Rods 24 supported in lugs 25 formed near the top and at each side of the bag holders 17 and 18 are each suitably secured adjacent one end to bag holder 17 and form guiding means for bag holder 18 which is slidable longitudinally along said rods. Each rod is threaded at its free end to receive a threaded nut 26 which serves to limit the extent of relative movement between the bag holders. Between the adjacent lugs of the bag holders 17 and 18, springs 27 are provided to absorb shock when the bag holders are brought together and other springs 28 are provided adjacent the free ends of the rods 24 to absorb shock when the bag holders are separated. The bag holder 17 is normally urged in a direction away from bag holder 18 by means of tension springs 29 secured at one end to the arm 16 and secured at their opposite ends to the rods 24.

The bag holders 17 and 18 are oppositely disposed with respect to one another and are provided along their outer surfaces with corrugations 32 against which the bag is clamped by the lower ends of the clamping members 19 and 20, provided with rubber pads or the like 19a and 20a, respectively. Intermediate its ends, clamping member 19 is rotatably supported on a transverse shaft 33 mounted in bearings provided by a pair of spaced-apart brackets 34 formed on the bag holder 17 and clamping member 20 is similarly supported on a shaft 35 mounted in bearing-forming brackets 36 provided on the bag-holder 18. The clamping member 19 is connected at its upper end by means of shaft 37 to one end of a link 38 which is pinned at its other end as at 39 to lugs 40 formed on the under side of the arm 16. The upper end of clamping member 20 is similarly connected by means of a shaft 41 to one end of a link 42 in turn connected to the operating mechanism for the bag holders and clamping members by means of a rod 43. Each pair of bracket members 34 and 36 also supports a separate shaft 44 each carrying an annular rubber member 45 serving as a cushioning stop for each of the clamping members when the latter are moved to bag releasing position as shown in the drawings.

The intermediate section 13 of the upright frame F houses a motor 50 preferably mounted on a bracket 51 hingedly connected as at 52 (Fig. 1), while the top section 14 of the frame houses the operating mechanism for the bag holders 17 and 18 and clamping members 19 and 20. In order to provide easy access to the motor 50 and to the bag holder operating mechanism, each of the intermediate and top sections of the frame is provided with removable side plates 53 and 54 (Fig. 2).

Referring to Fig. 2, the top section 14 is formed at one side thereof with an upstanding bracket support 55 for a main shaft 56 which is fixed to the support by means of a pin 57. Opposed roller type bearings 58 carried by the shaft 56 rotatably support a driven member 59 having a drum portion 60, an eccentric portion 61 and an enlarged pulley fly-wheel 62, the latter operatively connected to the motor 50 by means of the endless belts 63 and pulleys 64 carried on the shaft 65 of the motor.

Adjacent one end of the driven member 59, the shaft 56 carries a sleeve 66 forming a bearing for a clutch supporting plate 67 held in place by a

take-up plate 68 bolted or otherwise suitably secured to the end of the shaft 56. Projecting outwardly from the outer surface of the plate 67 is a crank pin 69 operating a connecting rod 70 which is slidably connected at its other end to rod 43 (Fig. 3). Threaded nuts 71 engaging complementary threads provided on the rod 43 serve to limit the extent of sliding movement of the connecting rod 70 and a coil spring 72 is provided adjacent one of the nuts 71 to form a resilient stop.

Cooperating with the drum portion 60 of the driven member 59 is a pair of oppositely disposed clutch members 75 pivotally supported at one end on a shaft 76 carried by the plate 67 adjacent the crank pin 69. Each clutch member is fitted with a suitable friction lining 77 which conforms to the outer periphery of the drum portion 60, as best seen from Fig. 6. The free ends of the clutch members 75 terminate in flattened straight portions 78 disposed in spaced-apart relation to receive therebetween a cam 79 rotatably mounted on a shaft 80 also carried by the plate 67 but diametrically opposite the shaft 76. Springs 81 on guide rods 82 cooperate with the clutch members 75 to clamp the latter against the periphery of the drum 60 for rotation of the clutch members and crank plate 67 as a unit, and the cam 79 cooperates with the flattened straight ends 78 of said clutch members to spread the latter apart and disengage their linings 77 from the drum portion 60.

The clutch cam 79 is formed with a lever portion 83 having a channel 84 along one edge thereof open at one end and terminating at its other end in a stop 85 (Figs. 8 and 9) adjacent which one wall of the channel 84 is provided with a cut-out portion 86 for the purpose hereinafter set forth.

On opposite sides thereof, the top section 14 is provided with sleeve bearings 88 and 89 in which vertical shafts 90 and 91 are journaled, each shaft carrying at its upper end a separate cam operating arm 92 and 93, respectively, adapted to cooperate with the cam lever 83. Each of the shafts 90 and 91 also carries at its lower end a separate lever 94 and 95, respectively, operatively connected together by means of clevises 96 and a transverse rod 97 extending beneath the top section 14. The transverse rod 97 is adapted to be reciprocated to impart angular rotation to the shafts 90 and 91 and bring the cam operating arms 92 and 93 into and out of alignment with the channel 84 of the cam lever 83. The cam operating arms 92 and 93 are so disposed with respect to one another that when one of the cam operating arms is moved into alignment with the channel 84 of the cam lever, the other cam operating arm is moved out of alignment, and vice versa. Adjustable stops formed by the clamping screws 98 on the operating arms 92 and 93 and by lugs 99 arranged in opposite sides of the top section 14 of the frame insure accurate alignment of the operating arms with the channel 84 as clearly shown in Fig. 3.

Referring again to Fig. 6, the rod 97 is normally biased in one direction to maintain the cam operating arm 92 in alignment with the channel 84 of the cam lever 83 and maintain cam operator 93 out of alignment with said channel through the medium of a spring 100 connected at one end to the intermediate section 13 of the frame F and connected at its opposite end to an eye member 101 suitably secured

to the rod 97. Movement of the rod 97 in the opposite direction against the tension of the spring 100 is brought about by means of a flexible cable 102 secured at one end to the eye member 101. The cable runs over pulleys 103 and 104 (Figs. 1 and 2) and is secured at its opposite end to a lever 105 carried by the inner end of a shaft 106 journalled in a sleeve bearing 107 supported by channel member 10. The outer end of the shaft 106 has secured thereto a foot pedal 108 adapted to be depressed to pull the cable 102.

Thus, with the foot pedal depressed, the cam operating arm 93 is brought into alignment with the cam lever 83 while the cam operating arm 92 is brought out of alignment with said lever.

Referring to Fig. 7, the shaking mechanism for the bag comprises a vertical lever 110 pivotally connected at its upper end to a pin 111 supported in the arm 16, said lever terminating at its lower end in a yoke 112 embracing the eccentric portion 61 of the driven member 59. Springs 113 housed in sockets 114 formed on the top section 14 of the frame F resiliently support arm 16. The compression of the springs 113 may be so adjusted by set screws 115 that when no bag or an empty bag is clamped on the bag holder 17 and 18, the arm 16 is raised sufficiently to prevent the top of the yoke 112 from engaging the eccentric portion 61 with the result that no shaking action will be imparted to the arm 16 as the lever 110 will merely oscillate about the pivot pin 111. However, as soon as the bag is partly filled, the additional weight compresses the springs 113 and the yoke is brought into contact with the eccentric portion 61 to shake the arm 16 up and down and in consequence thereof, impart a shaking action to the bag being filled to compact the contents of the bag; when the bag is released from the holders 17 and 18 the springs 113 again lift the arm 16 and raise the yoke clear of the eccentric portion 61 and shaking ceases.

Having described the details of construction of my improved bag filling machine unit, its operation is as follows:

The motor 50 is plugged into any suitable electrical outlet (not shown) and operates to rotate the driven member 59 continuously on the stationary shaft 56. The crank plate 67 is normally prevented from rotating with the driven member 59 by one or the other of the cam operating arms 92 and 93 in engagement with the channel 84 of the cam lever so that the clutch members 75 are disengaged from the drum portion 60 of the driven member 59. With the foot pedal 108 depressed and the cam operating arm 93 in engagement with the cam lever 83 as shown in Figs. 1 and 6, since the crank pin 69 on the plate 67 is at a position nearest the bag holders 17 and 18, the latter will occupy the position shown in Figs. 1, 3, 4 and 5, with the lower ends of the clamping members 19 and 20 away from the holders 17 and 18, respectively.

The operator slips the open mouth of the bag or like receptacle between the bag holders and the clamping members and then releases the foot pedal 108 to allow spring 100 to move rod 97 toward the right. This movement of the rod 97 rotates shafts 90 and 91 in a counterclockwise direction as viewed in Fig. 3 to move cam operating arm 93 out of engagement with the cam lever 83 through the opening 86 in one wall of the cam channel 84 and move cam operating arm 92 into alignment with the cam lever. As

soon as the cam operating arm 93 moves clear of the cam lever 83, the cam 79 is free to turn on the shaft 80 and the springs 81 will force the clutch members 75 together into engagement with the drum portion 60 of the driven member 59 to rotate the crank plate 67 through 180°, or one-half a revolution when the cam operating arm 92 enters the cam channel 83 to rotate the cam 79. This rotational movement of the cam 79 disengages the clutch members 75 from the drum portion 60 and the cam operating arm 92 comes into abutting engagement with the cam stop 85 on the cam lever 83 to arrest rotational movement of the crank plate 67.

During this rotation of the crank plate 67, the crank pin 69 thereof has pulled connecting rod 70 toward the right which first rocked clamping member 20 on its shaft 35 into clamping engagement with the bag holder 18, then moved the latter toward the right until it contacted and compressed springs 28, after which the bag holder 17 has also been pulled in the same direction. Inasmuch as the top of the clamping member 19 is connected to a relatively fixed point on the arm 16, while the fulcrum 33 of said clamping member has moved with the bag holder 17, the movement imparted to the bag holder 17 will rock the clamping member 19 into clamping engagement so that the mouth of the bag is thus distended and clamped to both of the bag holders 17 and 18 ready to be filled with material fed from a conventional hopper, not shown, through a filling opening 120 provided in the arm 16, as clearly shown in Figs. 1, 3 and 5.

As the filling proceeds, the weight of the bag overcomes the tension of the springs 113 which normally hold the arm 16 in slightly raised position and said springs are compressed to bring the top portion of the yoke 112 into engagement with the eccentric portion 61 of the driven member 59 to impart up and down shaking movement to the arm 16 to shake the bag together with its contents.

When the bag has been filled, the operator depresses the foot pedal 108 which, through the medium of the cable 102, pulls rod 97 against the tension of the spring 100 to rotate the shafts 90 and 91 in a clockwise direction as viewed in Fig. 3 to move cam operating arm 92 out of engagement with the cam lever 83 and move cam operating arm 93 into alignment for engagement with said cam lever. Upon disengagement of the cam operating arm 92 from the cam lever 83, the clutch members 75 are again brought into engagement with the drum portion 60 by the springs 81 and the crank plate 67 is rotated through another 180° until the cam operating arm 93 enters the cam channel 84 to turn the cam 79 and disengage the clutch member 75 from the drum portion 60. During this half revolution of the crank plate 67, the connecting rod 70 is moved toward the left and, as the rod begins its movement, the springs 29 will pull the bag holder 17 back to its normal position releasing the clamping member 19. Since the tension on the other clamping member 20 has also been released, the weight of the filled bag will cause the bag to slide off both of the holders. Continued movement of the connecting rod 70 to the left moves the bag holder 18 towards the bag holder 17 and the parts finally come to rest in the position shown in the drawings with the bag holders in contracted condition ready for the operator to place another bag thereon.

It is to be noted that during the operation of

the mechanism, the stop 35 of the cam lever 83 is brought into engagement with one or the other of the cam operating arms 92 and 93 with very little shock for the reason that before this action takes place, the clutch members 75 are wholly disengaged from the drum portion 60 by the turning action imparted to the cam 79 by engagement of the cam operating arm in the cam channel 84 so that only the inertia of the rotating parts must be overcome. Moreover, the springs 81 may be so adjusted that the clutch takes hold gradually and the crank plate 67 and clutch members 75 never acquire the full speed of the drum portion 60, thus reducing the energy that must be dissipated and insuring easy starting and stopping of the operating crank for the bag holding means.

It will also be noted that at the start of the rotational movement of the crank plate 67 either from the position shown in Fig. 1 when the bag holders are in contracted condition, or from the diametrically opposite position when such bag holders are in expanded position, the distance through which the crank pin 69 moves will increase gradually during the first quarter revolution and will likewise gradually decrease during the second quarter revolution thereby insuring easy starting and stopping of the operating crank. Furthermore, due to the novel crank drive for the bag holding means, there is a great multiplication of the force applied by the motor 50 through the clutch when the load is the heaviest which permits the use of a relatively small motor and saves wear on the clutch. At the starting point, when the crank pin 69 occupies the position shown in Fig. 1, the starting friction of the clamp 20 on its pivot 35 and of the bag holder 18 on the tracks 22 must be overcome. As the crank pin 69 approaches its diametrically opposed stopping point where several loads are encountered, namely tightly clamping the bag on the bag holders and compressing the springs 28 and 29, the pull of the connecting rod 70 will gradually increase and at the stopping point of the crank pin 69 the available force will be theoretically infinite.

It will be seen from the foregoing that not only have I provided a unitary structure embodying bag holding means and shaking means operated by a common motor, but I have also provided novel operating mechanism for the bag holding means which produces a simple harmonious motion insuring easy starting and stopping of the bag holding means without requiring any limiting stops. Moreover, the entire machine is self-contained and has both the bag-holding means and shaking means thereof operated by the same prime mover which requires only an electrical outlet to render the machine ready to operate.

No claim is made in the present case to the structure of the bag holding and clamping means disclosed as the same forms the subject matter of a separate application Serial No. 460,357 filed October 1, 1942.

From the foregoing it is believed that the construction, operation and advantages of my invention may be readily understood by those skilled in the art without further description, it being borne in mind that numerous changes may be made in the details disclosed without departing from the spirit of the invention as set out in the following claims.

What I claim is:

1. In a bag filling machine, in combination, movable bag-holding members for insertion into

the mouth of a bag or the like, clamping members pivotally mounted on said bag-holding members adapted to clamp the bag against said bag-holding members, and means including a rotatable crank and a reciprocatable connecting rod for moving said bag-holding members towards and away from each other and for moving said clamping members towards and away from said bag-holding members.

2. In a bag-filling machine, in combination, movable bag-holding members for insertion into the mouth of a bag or the like, clamping members pivotally mounted on said bag-holding members adapted to clamp the bag against said bag-holding members, reciprocatable means for moving said bag-holding members towards and away from each other and for moving said clamping members towards and away from said bag-holding members, and means including intermittently rotatable crank means for imparting intermittent reciprocatory movement to said reciprocatable means.

3. In a bag-filling machine, in combination, a pair of relatively movable bag-holding means for insertion into the mouth of a bag or the like, clamping members pivotally mounted to clamp the bag against said bag-holding means, reciprocatable means for moving said bag-holding means towards and away from each other and for moving said clamping members towards and away from said bag-holding means, rotatable crank means for reciprocating said reciprocatable means, a prime mover adapted to rotate continuously, and clutch means operable to connect and disconnect said crank means and said prime mover.

4. In a bag-filling machine, in combination, a pair of relatively movable bag-holding means for insertion into the mouth of a bag or the like, clamping members pivotally mounted to clamp the bag against said bag-holding means, reciprocatable means for moving said bag-holding means towards and away from each other and for moving said clamping members towards and away from said bag-holding means, a rotatable member, means for driving said rotatable member continuously, a crank wheel operatively connected to said reciprocatable means to reciprocate the latter, clutch means carried by said crank wheel and adapted to connect and disconnect said crank wheel and said rotatable member, and means for actuating said clutch means.

5. In a bag-filling machine, in combination, oppositely disposed bag holders movable towards and away from each other and adapted to be inserted into the mouth of a bag or the like, clamping members pivotally mounted on said bag holders and adapted to be moved towards and away from said bag holders to clamp and release, respectively, the said bag, a rotatable crank wheel and connecting rod for imparting reciprocatory movement to said bag holders and clamping members, a rotatable drum coaxial with said rotatable crank wheel, driving means for said drum, clutch means carried by said crank wheel and embracing the periphery of said drum, means normally urging said clutch means in clamping engagement with said drum to rotate said crank wheel and clutch as a unit and drive said connecting rod, and cam means operable at each 180° rotation of said crank wheel to disengage said clutch means from said drum and arrest rotation of said crank wheel at positions corresponding to expanded and contracted positions of said bag holders and correspond-

ing clamping and releasing positions of said clamping members.

6. In a bag filling machine, in combination, oppositely disposed bag holders movable towards and away from each other and adapted to be inserted into the mouth of a bag or the like, clamping members pivotally mounted on said bag holders and adapted to be moved into bag clamping and bag releasing positions, a rotatable crank wheel and connecting rod for moving said bag holders towards and away from each other and simultaneously actuating said clamping members to bag releasing and bag clamping positions, respectively, a rotatable drum coaxial with said crank wheel, driving means for said drum, clutch means carried by said crank wheel and embracing the periphery of said drum, means normally urging said clutch means into clamping engagement with said drum to drive said crank wheel, movable cam means carried by said crank wheel and adapted to disengage said clutch means from said drum, and a pair of cam operating members disposed diametrically opposite one another relative to said crank wheel and movable into and out of the path of said cam means.

7. In a bag filling machine, in combination, oppositely disposed bag holders movable towards and away from each other and adapted to be inserted into the mouth of a bag or the like, clamping members pivotally mounted on said bag holders and adapted to be moved into bag clamping and bag releasing positions, a rotatable crank wheel and connecting rod for moving said bag holders towards and away from each other and simultaneously actuating said clamping members to bag releasing and bag clamping positions, respectively, a rotatable drum coaxial with said crank wheel, driving means for said drum, clutch means carried by said crank wheel and embracing the periphery of said drum, means normally urging said clutch means into clamping engagement with said drum to drive said crank wheel, movable cam means carried by said crank wheel and adapted to disengage said clutch means from said drum, a pair of cam operating members disposed diametrically opposite one another relative to said crank wheel and movable into and out of the path of said cam means, and means operatively connecting said cam operating means for movement of one of said cam operating means into the path of said cam means and simultaneous movement of the other of said cam operating means out of the path of said cam means.

8. In apparatus of the class described including bag holding means movable selectively to bag engaging and bag releasing positions; the combination of a rotatable crank wheel, a prime mover, means operable to connect and disconnect said crank wheel and prime mover to impart intermittent rotational movement to said crank wheel, and means operatively connecting said crank wheel and said bag holding means.

9. In apparatus of the class described including bag holding means movable selectively to bag engaging and bag releasing positions; the combination of a rotatable crank wheel, a rotatable drum, driving means for said drum, a pair of oppositely disposed clutch members carried by said crank wheel and embracing the periphery of said drum, means normally urging said clutch means into clamping engagement with said drum for rotation of the crank wheel, cam means operable to disengage said clutch means from said drum at each 180° of rotation of said crank

wheel, and means operatively connecting said crank wheel and said bag holding means.

10. In a machine of the class described including bag holding means movable selectively to bag engaging and bag releasing positions; the combination of a rotatable crank wheel, a rotatable drum, driving means for said drum, a pair of oppositely disposed clutch members carried by said crank wheel and embracing the periphery of said drum, means normally urging said clutch members into clamping engagement with said drum for rotation of the crank wheel, a movable cam carried by said crank wheel and adapted to disengage said clutch members from said drum, an operating lever for said cam projecting beyond the periphery of said crank wheel, a pair of arms mounted adjacent opposite sides, respectively, of said crank wheel and movable selectively into and out of the path of movement of said lever to actuate said cam and arrest rotational movement of said crank wheel at each 180° of rotation, and means operatively connecting said crank wheel and said bag holding means.

11. In a machine of the class described including bag holding means movable selectively to bag engaging and bag releasing positions; the combination of a rotatable crank wheel, a rotatable drum, driving means for said drum, a pair of oppositely disposed clutch members carried by said crank wheel and embracing the periphery of said drum, means normally urging said clutch members into clamping engagement with said drum for rotation of said crank wheel, a movable cam carried by said crank wheel and adapted to disengage said clutch members from said drum, an operating lever for said cam projecting beyond the periphery of said crank wheel, a pair of arms mounted adjacent opposite sides, respectively, of said crank wheel and movable selectively into and out of the path of movement of said lever to actuate said cam and disengage said clutch members from said drum at each 180° of rotation of said crank wheel, a cam channel in said operating lever adapted to be engaged by said arms selectively, to arrest rotational movement of said crank wheel, and means operatively connecting said crank wheel and said bag holding means.

12. A bag holding and shaking unit comprising an upright frame having a supporting base portion, a substantially horizontal support hingedly mounted at one end to one side of said frame and extending across the top of the latter, bag holding means mounted adjacent the free end of said horizontal support for suspending an open-mouth bag or the like for the filling operation, said bag holding means being movable respectively to bag clamping and bag releasing positions, a rotatable member mounted in said frame and having a drum portion and an eccentric portion, means for driving said rotatable member continuously, a crank wheel coaxial with said rotatable member, means operatively connecting said crank wheel to said bag holding means to actuate the latter, clutch means adapted to cooperate with the drum portion of said rotatable member and operable selectively to connect and disconnect said crank wheel and said rotatable member, spring means normally maintaining said horizontal support in slightly raised position and adapted to be compressed by the weight of a bag being filled, and means carried by said horizontal support adapted to cooperate with the eccentric portion of said rotatable member upon compression of said spring means to

impart vertical vibratory movement to said horizontal support and shake the suspended bag together with its contents.

13. A portable machine for supporting bags or the like for filling comprising a frame having a supporting base and a vertical housing, a laterally extending arm hingedly secured at one end for vertical swinging movement to the upper end of said housing, bag holding means slidably mounted on said arm adjacent the free end of the latter to permit a bag to be suspended therefrom for filling and being movable respectively to bag holding and bag releasing positions, a rotatable member in said housing having a drum portion and an eccentric portion, a motor in said housing having a driving connection with said rotatable member to rotate the latter continuously, a rotatable crank wheel adjacent said rotatable member, a connecting rod driven by said crank wheel and operatively connected to said bag holding means to move the latter from one position to the other and vice versa, a friction clutch carried by said crank wheel and adapted to cooperate with said drum portion to drive said crank wheel, means normally maintaining said clutch in frictional engagement with said drum portion, cam means carried by said crank wheel and movable to disengage said clutch from said drum portion, separate cam operating means in said housing arranged diametrically opposite one another relative to said crank wheel and mounted for movement into and out of the path of said cam means, mechanism operatively connecting said cam operating means together for movement of one of said cam operating means out of the path of said cam means to permit engagement of said clutch with said drum portion and simultaneous movement of the other of said cam operating means into the path of said cam means for disengagement of said clutch from said drum and braking of said crank wheel, whereby said crank wheel is driven intermittently, spring means normally maintaining the free end of said laterally extending arm in a predetermined position relative to a horizontal plane and permit the same to be lowered slightly by the weight of a bag being filled, and means cooperating with the eccentric portion of said rotatable member and operable when said arm is in lowered position to oscillate the latter on its hinge whereby to shake the suspended bag and its contents during filling.

14. In a bag holding machine, in combination, bag holding means movable respectively to bag holding and bag releasing positions, a crank wheel and connecting rod unit for moving said bag holding means from one position to the other and vice versa, driving means for said unit, and means operable to connect and disconnect said driving means and said unit at each 180° of rotation of the crank wheel corresponding to bag holding and bag releasing positions, respectively, of said bag holding means.

15. In a machine of the class described including bag-holding means movable selectively to bag engaging and bag releasing positions and arranged in an elevated plane whereby to permit a bag or the like to be suspended therefrom for

filling; the combination of rotatable means including a drum portion and an eccentric portion, driving means for said rotatable means, and motion transmitting mechanism including means cooperating with the drum portion of said rotatable means to move said bag holding means from one position to the other and vice versa, and means cooperating with the eccentric portion of said rotatable means to impart vertical vibratory movement to said bag holding means.

16. A portable machine for supporting bags or the like for filling comprising a frame having a base portion and an upright portion, a laterally extending arm hingedly secured at one end to the upper part of said upright portion of the frame and carrying bag-holding means adjacent its free end to permit a bag to be suspended therefrom for filling, means normally maintaining said arm in a substantially horizontal plane and permit the same to be tilted slightly by the weight of a bag being filled, and means operatively connected to said arm and operable when the latter is in tilted position to oscillate said arm on its hinge whereby to shake a suspended bag and its contents during filling.

17. Apparatus of the class described comprising, in combination, a portable structure including a supporting base portion, an upright housing portion, and a laterally extending substantially horizontal top portion secured at one end to the upper part of said upright portion; bag holding means carried by said horizontal top portion adjacent the free end of the latter and movable selectively to bag engaging and bag releasing positions; and mechanism in said housing portion including a rotatable crank element operatively connected to said bag holding means and rotatable intermittently to move said bag holding means from one position to the other and vice versa.

18. Apparatus of the class described comprising, in combination, a portable structure including a supporting base portion, an upright housing portion and a laterally extending substantially horizontal top portion hingedly secured at one end to the upper part of said upright portion; bag holding means carried by said horizontal top portion adjacent the free end of the latter to permit a bag to be suspended therefrom for filling and being movable selectively to bag engaging and bag releasing positions; means normally maintaining the free end of said horizontal top portion in a predetermined plane and permitting the same to be lowered slightly by the weight of a bag being filled; rotatable means in said housing portion having a drum portion and an eccentric portion; driving means for said rotatable means; means operatively connected to said bag holding means and cooperating with the eccentric portion of said rotatable means when the free end of said top portion is in lowered position to oscillate the latter on its hinge whereby to shake a suspended bag and its contents.

JACOB J. NEUMAN.
